UNITED STATES PATENT OFFICE

JOHN MORRIS, OF BAYONNE, NEW JERSEY, ASSIGNOR TO INTERNATIONAL COMBUSTION ENGINEERING CORPORATION, OF NEW YORK, N. Y., A CORPORATION OF DELAWARE

STOKER

Application filed July 11, 1928. Serial No. 291,756.

My invention relates to stokers, and has special reference to traveling grate stokers of the Coxe type.

An object of the invention is to provide novel and improved fuel supporting members for a stoker of this type.

Another object of the invention is to provide means of simple and strong construction for securing the fuel supporting keys of a traveling grate stoker in place, whereby they may be easily attached and detached and when attached are securely held.

A still further object of my invention is to provide an end locking key for a carrier bar of a traveling grate stoker of the character indicated, on which the same combustion efficiency may be maintained as on the other keys.

The several features of the invention, whereby these and other objects may be attained, will be clearly understood from the following description and accompanying drawings, in which:

Figure 1 is a plan view of a portion of the traveling grate of a Coxe stoker embodying the features of my invention in their preferred form;

Fig. 2 is a detail view in perspective of one of the fuel supporting keys shown in Fig. 1;

Fig. 3 is a side view of another one of the keys shown in Fig. 1, a section of the usual carrier bar for the keys being shown; and

Fig. 4 is a sectional view on a reduced scale taken on the line 4-4 of Fig. 1.

My invention is at present embodied in a traveling grate stoker of the Coxe type. In this type of stoker, the traveling grate is made up of a plurality of banks of fuel supporting keys 2 arranged one behind the other, with the keys in each bank arranged side by side. Each bank of keys is supported on a carrier bar extending transversely of the stoker, one of which being indicated at 4. Each of these carrier bars is provided with a

sunken web portion 6 having fuel supporting portions formed on its ends, one of which is indicated at 8, the ends of the bar being secured on sprocket chains (not shown) which are mounted on sprocket wheels. On the web portion 6 of each carrier bar there is secured a dove-tail or undercut rib 10 having one end thereof spaced from the associated fuel supporting portion 8. The fuel supporting keys 2 are provided with a dove-tail recess 11 to permit the keys to be passed successively over the spaced end of the dove-tail rib 10 so as to position them on the web in side by side relation, the gap provided at said end of the web permitting the keys to be thus applied.

In accordance with my invention, the outermost one of the keys 2 on the dove-tail rib 10 has its outer side flush with the end of the rib, and an additional key 12 is provided for closing the space between the end of said outermost key and the fuel supporting portion 8 and for holding the several keys in proper position on said rib.

The rear portion of the outermost key on the rib 10 is provided with a laterally projecting lug 14 having its underside semi-cylindrical, and having a vertically extending slot 16 on its forward side spaced from its outer end.

The key 12 is of substantially the same shape and size as the other keys except that, in place of a dove-tail recess in its under side, it is provided with legs 18 that rest upon the web 6. The rear portion of the key 12 is provided with a semi-cylindrical recess 20 extending transversely thereof and opening upwardly for receiving the lug 14, the forward portion of the wall of the recess having a rearward projection 22 which is received in the slot 16 in the lug 14.

The forward ends of the key 12 and the outermost key on the rib 10, are detachably secured together by means of a cotter pin 24 which extends through apertures 26 in said

ends of the keys, the outer ends of said apertures being countersunk and the countersunk portions opening forwardly and upwardly as shown.

5 When the key 12 is in position, its rear portion is securely held in place by the lug 14 which interlocks with the wall of the recess 20, and its forward end is held by the cotter pin 24. The projection 22 in the slot 16 locks the two keys so that they are continuously in close contact at their rear ends which prevents the rear end of the outermost key on the dove-tail rib from sliding in a horizontal direction along the rib, thereby preventing a 10 fuel leakage and maintaining the proper air space between the two keys for the proper combustion of the fuel bed. The legs 18 of the key 12 are so designed and located that they act as a lock against the end of the dove-tail rib, keeping the key 12 at all times in a position adjacent to the fuel supporting member 8, while providing ample air space for the ignited fuel over the key and discharging the siftings when the face of the carrier bar reaches a vertical position. It will be apparent that the key 12 is so constructed that the same combustion efficiency may be maintained thereon as on the other keys on the carrier bar. The key 12 may be easily 15 removed to permit removal of the other keys in the bank when the bank reaches a position part way around the forward drum of the traveling grate, the ends of the banks being then separated from the adjacent banks. To 20 remove the key 12, the cotter pin 24 is first removed, the ends of the pin being easily accessible through the forwardly opening countersunk portions of the apertures 26. The forward end of said key is then swung 25 upwardly until the rear edge of the wall of the recess 20 passes beneath the lug 14, whereupon the key 12 may be lifted from the grate.

To apply the key 12, its rear end is passed beneath the lug 14 so as to cause the recess 20 to receive the lug, and then the cotter pin is 30 inserted and its end spread to hold the forward ends of the two keys together.

Such removal and replacement of the keys may be accomplished while the stoker is in 35 operation, which, of course, is a feature of great practical importance as it overcomes the necessity of more or less frequent shutdowns.

It will be apparent in accordance with my 40 invention, that a simple, strong and convenient means is provided for securing the end key of a bank of keys in place; and, also, that as the end key is secured to the adjacent key in the bank, it may be of the same width 45 and have the same area of fuel supporting surface as the other keys.

As will be evident to those skilled in the art, my invention permits various modifications without departing from the spirit thereof or the scope of the appended claims.

What I claim is:

1. In a traveling grate stoker, a carrier bar, and fuel supporting members mounted on the bar in side by side relation, one of said members having a laterally projecting lug 70 and an adjacent member having a recess for receiving the lug, the lug and recess being so shaped as to hold said members from relative lateral movement.

2. In a traveling grate stoker, a carrier 75 bar, fuel supporting members mounted on the bar in side by side relation, one of said members having a laterally projecting lug near one end thereof, and an adjacent member having a recess for receiving the lug and 80 means for detachably securing the last two mentioned members together near the end opposite to said lug.

3. In a traveling grate stoker, a carrier bar, fuel supporting members mounted on 85 the bar side by side and extending longitudinally of the stoker, the rear portion of one of said members having a laterally projecting lug, and an adjacent member having a substantially semi-cylindrical recess opening 90 upwardly for receiving said lug, and means for detachably securing the forward portions of the last mentioned members together.

4. In a traveling grate stoker, a carrier bar, fuel supporting members mounted on the bar side by side and extending longitudinally of the stoker, the rear portions of two of 95 said members having interlocking portions, and means for detachably securing the forward portions of the last two mentioned members together.

5. In a traveling grate stoker, a carrier bar, fuel supporting members mounted on the bar in side by side relation and extending 105 longitudinally of the stoker, the rear portion of one of said members having a laterally projecting lug having its under surface substantially semi-cylindrical and an adjacent member having a substantially cylindrical 110 recess opening upwardly for receiving said lug, said lug having a vertically extending slot in its forward side, and the wall of said recess having a projection extending into said slot, and means for detachably securing 115 the forward portions of said last two mentioned members together.

6. In a traveling grate stoker, a carrier bar having a web and a raised fuel supporting portion at one end of said web, a dove-tail rib on said web having one end thereof spaced from said fuel supporting portion, fuel supporting keys mounted on said web having dove-tail recesses in their under sides 120 so as to permit them to be successively passed through the space at said end of the rib and over said end so as to be positioned on the rib in side by side relation, a fuel supporting key positioned between the endmost key 125 on said rib and said fuel supporting portion, 130

the forward portion of the last-mentioned key having a substantially cylindrical recess opening upwardly, and the next adjacent key having a lug extending into said recess, and means for detachably securing the forward portions of the last two mentioned keys together.

In testimony whereof, I have signed my name to this specification this 9th day of July, 1928.

JOHN MORRIS.
